(57) **CLAIM**

The ornamental design for a transaction card, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a transaction card showing our new design;

FIG. 2 is a top view thereof, the bottom view being a mirror image thereof;

FIG. 3 is a front view thereof;

FIG. 4 is a right side view thereof, the left side view being a mirror image thereof; and,

FIG. 5 is a rear view thereof.

The broken line showing of portions of the transaction card is included for the purpose of illustrating environmental structure and forms no part of the claimed design.

1 Claim, 3 Drawing Sheets
